No. 729,912.

PATENTED JUNE 2, 1903.

G. K. ANDREWS.

TETHER.

APPLICATION FILED SEPT. 6, 1902.

NO MODEL.

UNITED STATES PATENT OFFICE.

GEORGE K. ANDREWS, OF WEBSTER GROVES, MISSOURI.

TETHER.

SPECIFICATION forming part of Letters Patent No. 729,912, dated June 2, 1903.

Application filed September 6, 1902. Serial No. 122,373. (No model.)

To all whom it may concern:

Be it known that I, GEORGE K. ANDREWS, a citizen of the United States, residing in Webster Groves, in the county of St. Louis 5 and State of Missouri, have invented a certain new and useful Improvement in Tethers, of which the following is a full, clear, and exact description, reference being had to the accompanying drawings, forming part of this specification.

My invention relates to a revolving tether, to which an animal, such as a horse, may be attached to permit of its grazing over a limited area without liability of becoming tangled in the strap or rope by which it is held.

My invention consists in features of novelty hereinafter fully described, and pointed out in the claims.

Figure I is a perspective view of my tether. 20 Fig. II is an enlarged vertical section taken through the post of the tether and the bearing between the revolving frame and said post. Fig. III is a horizontal section taken on line III-III, Fig. II.

25 1 designates the upright post of the tether, which is mounted on a cross-frame 2, and 3 are braces connecting the outer ends of the cross-frame to the post. Approximately midway of the height of the post 1 is a shoulder 4.

30 5 designates a horizontal top bar that is loosely mounted on the post 1 to revolve thereon.

35 6 designates braces fixed to the top bar 5, that with said top bar constitute a revolving frame that may rotate with respect to the post 1.

40 7 is a pole secured to the top bar 5 by clips 8 and provided at its outer end with a knob 9.

45 10 designates a sleeve fitted to the post 1 and adapted to rest on the shoulder 4 of said post. This sleeve is provided centrally with an annular rib 11.

12 designates an upper bearing-ring that 45 rests upon the annular rib 11, said ring being provided with upwardly-projecting arms 13, to which the revolving-frame braces 6 are attached for their support.

14 designates fingers extending downwardly from the upper bearing-ring 12.

15 is a lower bearing-ring surrounding the

sleeve 10 beneath the rib 11 and provided with apertures 16, that receive the fingers 14 of the upper bearing-ring 12. The ring 15 is upheld by keys 17, seated in the fingers 14. The lower bearing-ring 15 is provided with an extension 18, that contains a hole 19 which receives one end of a balance-spring 20. The opposite end of the spring is connected to an adjustment-rod 21, that 55 passes through a strap 22, attached to the top revolving-frame bar 5. The upper end of the rod 21, which passes through said strap, is threaded and receives an adjustment-nut 23, by which the rod may be adjusted longitudinally to vary the tension of the spring 20.

In the practical use of the tether the revolving frame may be rotated on the post 1, in which movement it is supported by the 70 upper ring 12, to which the frame brace-bars 6 are attached. The lower ring 15, in connection with the spring 20 and its adjustment-rod, constitutes a balance for the pole 7, extending from the opposite side of the frame, 75 the balance being secured by reason of the spring 20 exerting a downward pull upon the rear side of the revolving frame to counter-balance the pole, the proper degree of balancing action being secured through the adjustment of the nut 23 on the adjustment-rod 21. It will be seen that as the lower bearing-ring 15 is loosely positioned beneath the annular rib 11 of the sleeve 10 and its adjustment to the upper bearing-ring by the 80 fingers 14 it revolves freely with the pole-carrying frame, and the spring 20 is constantly held in the proper position opposite to the extending pole to counterbalance it.

85 24 is a ring adapted to travel on the pole 7, 90 its outward movement being limited by the knob 9.

95 25 is a halter that may be applied to the head of the animal hitched to the tether, the halter being connected to the ring 24 by a rope 26, connected with the halter by means of a ring 29 and provided at the other end with a snap 27, the ring 29 sliding upward on the halter jaw-piece 30 when the head of the animal is lowered, thus carrying and holding 100 the rope so far off the ground that the animal when grazing cannot entangle its feet therein.

28 is a coil expansion-spring, one end of which is adjustably held to the halter-rope 26 to provide any desired amount of slack that may be drawn upon by the animal due to 5 the expansion of the spring 28 under stress, the spring serving to take up the rope when relieved from strain to reinstate the slack therein.

I claim as my invention—

- 10 1. In a tether, the combination of a post, a top bar rotatably mounted on said post, a pole carried by said bar, a revolving member encircling said post, a pair of braces interposed between said top bar and said revolving member, and a counterbalance-spring connected to said revolving member, and said top bar, substantially as set forth.
- 15 2. In a tether, the combination of a post, a top bar rotatably mounted on said post, a pole carried by said bar, a revolving member encircling said post, a counterbalance-spring connected to said revolving member, and an adjustment-rod forming a connection between said spring and said top bar, substantially as set forth.
- 20 3. In a tether, the combination of a post, a revolving frame mounted on said post, a pole carried by said frame, a sleeve fitted to said post, an annular rib on said sleeve, an upper bearing-ring attached to said revolving frame and resting on said rib, a lower bearing-ring encircling said sleeve below said rib, and a counterbalance-spring connected to said
- 25
- 30

lower bearing-ring and to said revolving frame, substantially as set forth.

35

4. In a tether, the combination of a post, a revolving frame mounted on said post, a pole carried by said frame, a sleeve fitted to said post, an annular rib on said sleeve, an upper bearing-ring attached to said revolving frame and resting on said rib, a lower bearing-ring encircling said sleeve below said rib, a counterbalance-spring connected to said lower bearing-ring, and an adjustment-rod connecting said spring to said revolving frame, substantially as set forth.

40

5. In a tether, the combination of a post, a revolving frame consisting of a top bar surmounting said post and brace-bars extending downwardly therefrom, a sleeve fitted to said post, an annular rib projecting from said sleeve, an upper bearing-ring seated on said rib and to which said braces are attached, fingers depending from said upper ring, a lower bearing-ring positioned beneath the rib of said sleeve and provided with apertures that receive the fingers of the upper bearing-ring, and a counterbalance-spring connected to said lower bearing-ring and to the top bar of the revolving frame, substantially as set forth.
